Patented Oct. 6, 1914.

THE NORRIS PETERS CO., PHOTO-LITHO., WASHINGTON, D. C.

UNITED STATES PATENT OFFICE.

CARL A. CARRICK, OF MARKEY, MICHIGAN.

REVOLVING DIVIDER FOR MOWING-MACHINES.

1,112,768.

Specification of Letters Patent.

Patented Oct. 6, 1914.

Application filed October 31, 1912. Serial No. 728,905.

To all whom it may concern:

Be it known that I, CARL A. CARRICK, a citizen of the United States, residing at Markey, in the county of Roscommon, 5 State of Michigan, have invented certain new and useful Improvements in Revolving Dividers for Mowing-Machines; and I do hereby declare the following to be a full, clear, and exact description of the invention, 10 such as will enable other skilled in the art to which it appertains to make and use the same.

This invention relates to revolving dividers for mowing machines and has for an 15 object to provide a novel hinge connection for attaching the divider to the finger bar shoe, this connection preventing rocking downward of the divider below a predetermined angle relatively to the shoe, but permitting of the divider rocking freely upward to rise over obstructions.

With the above object in view the invention consists of certain novel details of construction and combination of parts herein- 25 after fully described and claimed, it being understood that various modifications may be made in the minor details of construction within the scope of the appended claim.

In the accompanying drawing forming 30 part of this specification:—Figure 1 is a plan view of the improved rotary divider attached to a mowing machine finger bar. Fig. 2 is a side elevation of the parts shown in Fig. 1. Fig. 3 is a cross sectional view 35 taken on the line 3—3 Fig. 2. Fig. 4 is a cross sectional view taken on the line 4—4 Fig. 2. Fig. 5 is a cross sectional view taken on the line 5—5 Fig. 2. Fig. 6 is a perspective view of several parts of the hinge. Fig. 40 7 is a vertical longitudinal sectional view through a portion of the rotary divider, parts being shown in elevation.

Referring now to the drawing in which like characters of reference designate similar parts, 10 designates the shoe of a finger bar 11, the shoe being formed with a vertical slot 12 in which a ground wheel 13 is revolvably mounted, and further being formed in rear of this slot with a vertical slot 14.

50 The revolving divider comprises a central shaft 15 provided at one end with a securing eye 16 and a plurality of longitudinal wires 17 the inner ends of which are inserted through a washer 18 carried on the shaft 55 and clamped thereto by nuts 19 threaded on to each wire and bearing against the

opposite sides of the washer, the outer ends of the wires terminating in flared heads 20 which are clamped between two circular disks 21 by means of bolts 22 passed through the disks, the disks being provided in their confronting faces with annular substantially V-shaped recesses 23 which receive the heads of the wires. The disks and washers together with the wires are all turned on the 60 shaft in a direction opposite to the standing grain by frictional contact of the wires with the standing grain.

For attaching the rotary divider to the shoe a bolt 24 is passed horizontally through the slot 14 in the shoe and is held stationary in any adjusted position longitudinally of the slot by means of a lock washer 25 which is provided on both faces with serrations 26 and 27, the serrations 26 on the inner face 70 engaging with corresponding serrations 28 on the shoe, and the serrations 27 on the outer face engaging in corresponding serrations 29 on the opposing face of the flange 30 carried by a tube 31 which is fixedly 75 mounted on the bolt 24 and is clamped against the washer by means of the retaining nut 32 on the bolt. The tube flange is provided on one side with a lug 33 the purpose of which will presently be explained. 80

A tubular bearing 34 is revolvably mounted on the tube 31 and is provided on one side with a lug 35 through which and the securing eye 16 of the shaft 15 a bolt 36 is passed to secure the divider to the bearing 34, the 90 latter as above stated being adapted to rotate on the tube 31 and thus permit of the divider rocking in a vertical plane. A retaining washer 37 is held on the bolt 24 by means of the retaining nut thereof and bears 95 against the tubular bearing to retain the latter in place.

For limiting the rocking movement of the bearing, the latter is provided on the top face with a lug 38 which extends in a plane 100 at substantially a right angle to the lug 35 of the bearing and is adapted to contact with the above mentioned lug 33 on the tube flange 30, and limit rocking movement of the divider which as is clear is fixed to the 105 bearing, below a predetermined angle relatively to the shoe, while at the same time the divider may rock upwardly freely to clear obstructions such as stones, stumps and the like, since the bearing rotates in a 110 forward direction during upward rocking movement of the divider and the lug 38 of

the bearing moves forward out of contact with the lug 33 of the tube.

For permitting of the divider being adjusted laterally the lug 33 is equipped with 5 serrations 39 and a serrated washer 40 is fitted on the square bolt 36 and engages the serrations 39. A washer 41 is fitted on the bolt 36 between the nut 42 thereof and the securing eye 16 of the divider shaft. By 10 loosening the nut the serrated washer 40 may be disengaged from the serrations 39 and permit of the bolt being rotated to set the divider at any desired angle.

What is claimed, is:—

The combination with a sickle bar shoe having a vertical slot therein and having one side face roughened on the side edges of said slot, of a pivot pin engaged through said slot, a washer non-rotatably mounted

on said pivot pin and having a roughened 20 face engaging with the roughened edge portions of said slot for adjustably anchoring said pivot pin in said slot, a sleeve non-rotatably mounted on said pivot pin and having a roughened portion engaging with 25 a roughened face of said washer, a revolute hub on said sleeve, means for retaining said hub in place, stops carried by said sleeve and said hub for limiting rotation of said hub in both directions, and a divider 30 carried by said hub.

In testimony whereof, I affix my signature, in the presence of two witnesses.

CARL A. CARRICK.
